UNITED STATES PATENT OFFICE.

WALTER N. WAYMAN, OF STAUNTON, VIRGINIA.

MOLD.

No. 901,133.

Specification of Letters Patent.

Patented Oct. 13, 1908.

Application filed March 9, 1908. Serial No. 420,019.

To all whom it may concern:

Be it known that I, WALTER N. WAYMAN, a citizen of the United States, residing at Staunton, in the county of Augusta and 5 State of Virginia, have invented certain new and useful Improvements in Molds; and I do declare the following to be a full, clear, and exact description of the invention, such as will enable others skilled in the art to 10 which it appertains to make and use the same.

This invention relates to improvements in molds.

The object of the invention is to provide 15 a hollow mold having means whereby a current of water is caused to circulate therethrough to keep the molds cool and to prevent burning on, warping, or melting of the molds.

20 With this and other objects in view, the invention consists of certain novel features of construction, combination and arrangement of parts as will be described and particularly pointed out in the appended claims.

25 In the accompanying drawings, Figure 1 is a side view of a mold constructed in accordance with the invention, and showing the parts in closed position; Fig. 2 is a vertical sectional view of the same, showing the 30 parts open; Fig. 3 is a cross sectional view with the parts in a closed position; and Fig. 4 is an inner side view of one of the parts or sections of the mold.

Referring more particularly to the drawings, 35 1 denotes the mold, which may be of various forms or shapes, for casting various articles, the same being shown in the present instance as constructed for casting sash weights. The mold is formed in two hollow 40 sections, 2 and 3, which are formed of metal and have their inner or engaging sides depressed in the proper shape to form the article to be molded.

The mold section, 2, is preferably supported upon an arm or bar, 4, the lower end 45 of which is bolted or otherwise secured to a suitable base piece, 5. To the lower end of the section, 2, is connected a water inlet pipe, 6, said pipe being connected to a main supply pipe, 7. To the opposite end of the 50 section 2 is connected an overflow pipe, 8, the opposite end of which is connected to a main overflow pipe, 9. To the lower end of the mold section 3, is connected a flexible 55 water inlet pipe, 10, the opposite end of

which is connected to the supply pipe, 7, as shown. The upper end of the section 3 has connected thereto a flexible overflow pipe, 12, the opposite end of which is connected to the main overflow pipe. By means of 60 the main and branch supply pipes and the overflow pipes connected to the upper end of the mold section, a current of water is caused to circulate through the mold sections and thus keep the same cool. 65

Connected to each side of the stationary mold section 2 are laterally projecting arms, 13, to the outer ends of which are pivotally connected a bell-crank operating lever, 14, one arm of which forms a handle, 15, while 70 the opposite arm is connected to the movable mold section 3 by a link, 16. The mold section 3 is preferably provided on each side with an offset lug, 17, having formed therein a guide passage through which the arms 13 75 extend, said arms thus forming a support upon which the mold section, 3, is adapted to slide when the mold is open or closed. In closing the mold sections, the handle end of the bell crank lever 14 is swung upwardly, 80 thereby causing the opposite end to move inwardly and thus force the section 3 of the mold into engagement with the stationary section, 2. The flexible water supply and overflow pipes, 10 and 12, permit the section 85 3 to be readily moved into operative and inoperative positions. After the sections of the mold have been closed, the metal is poured into the upper end of the depression formed in the meeting sides of the sections, 90 and the article cast. After the cast articles become cool, the lever, 14, is operated to draw the section 3 out of engagement with the section 2, thus permitting the article to be dropped out between the lower portions 95 of the mold sections.

From the foregoing description, taken in connection with the accompanying drawings, the construction and operation of the invention will be readily understood without requiring a more extended explanation. 100

Various changes in the form, proportion and the minor details of construction may be resorted to without departing from the principle or sacrificing any of the advantages of 105 the invention, as defined in the appended claims.

Having thus described my invention, what I claim as new and desire to secure by Letters-Patent, is:

1. A mold of the character described comprising hollow sections adapted to be moved into and out of engagement with each other, a main water supply pipe, a main overflow pipe, and branch supply and overflow pipes to connect said sections of the mold with said main supply and overflow pipes, substantially as described. 25
2. A mold comprising a plurality of hollow sections, means to hold one of said sections stationary, a water supply pipe, an inlet pipe connecting said supply pipe with said stationary section of the mold, a flexible supply pipe adapted to connect said movable section with said main supply pipe, a main overflow pipe, a branch overflow pipe adapted to connect the upper end of said stationary section of the mold with said main overflow pipe, a flexible overflow pipe adapted to connect the other section of the mold with said main overflow pipe, and means whereby the movable section of the mold is moved into and out of engagement with the stationary section, substantially as described. 30
3. A mold of the character described comprising a pair of hollow sections, one of which is held stationary, water supply and discharge pipes connected to said sections, supporting arms fixedly mounted on one of said sections and slidably engaged with the opposite section, a bell-crank lever in the outer end of said arm, and a link to connect said lever with said movable section whereby the latter is moved into and out of engagement with the stationary section to close and open the mold, substantially as described. 35

In testimony whereof I have hereunto set my hand in presence of two subscribing witnesses.

WALTER N. WAYMAN.
